UNITED STATES PATENT OFFICE.

FRANK MONROE PRATHER, OF LOS ANGELES, CALIFORNIA.

SPRING-FELLY.

1,079,925.

Spécification of Letters Patent. Patented Nov. 25, 1913.

Application filed February 24, 1913. Serial No. 750,427.

To all whom it may concern:

Be it known that I, FRANK M. PRATHER, a citizen of the United States, residing at Los Angeles, in the county of Los Angeles and State of California, have invented a new and useful Spring-Felly, of which the following is a specification.

This invention relates to spring fellys and one object of the invention is to cause any eccentric position between the felly members when in operation, caused by a load, to distribute the load equally on all of the springs. Under load, each spring will be elongated the same distance.

15 A further object is to so arrange the springs that they will bring the felly members to concentric position when not under load, whether evenly distributed or evenly tensioned or balanced.

20 A further object is to provide a construction whereby springs may be used which will sustain the heaviest loads and yet be sensitive to respond to slight variations with light loads.

25 Another object is to provide a construction which will permit one felly member to move circumferentially with respect to the other member and such movement being resisted by all of the springs, thereby removing motor shock when the felly is used on a driving wheel.

Other objects and advantages will be brought out in the following description.

Referring to the drawings: Figure 1 is a 35 side elevation of a wheel equipped with my invention, part of the side plate being removed. Fig. 2 is an enlarged section on line x^2-x^2 , Fig. 1. Fig. 3 is an enlarged side elevation of a portion of the felly showing 40 the method of attaching the springs. Fig. 4 is a section on line x^4-x^4 , Fig. 2. Fig. 5 is a perspective of an outer spring fastener. Fig. 6 is a perspective of a slotted disk which locks the spring fastener in place.

45 The felly comprises two members, an inner member 1 and an outer member 2, the latter being formed in two sections 3 with an annular rabbet 4. The outer member 2 carries the tire 5. The outer member is flexibly supported with relation to the inner

member by coil springs which are arranged transversely of the felly and are connected between the two members. Thus one end of each spring is connected to one of the felly members, while the other end of each spring is connected to the other felly member. The 55 springs are arranged in two sets, the springs of the respective sets being attached to the same felly member so as to exert an opposing pull on the said felly member. 60

In the present embodiment I have shown the inner member 1 as provided with a center rib 6 and the outer member 2 with inwardly projecting ribs 7. One set of coil springs 8 is stretched between the rib 6 and 65 one of the ribs 7, and the other set of springs 8 is stretched between the rib 6 and the other rib 7, so that the two sets of springs act to hold the two felly members from transverse movement with respect to each 70 other. These springs are staggered as indicated in Fig. 4 and may be secured in position in any desired manner. As herein shown I provide spring fasteners 9 which are swiveled in the rib 6, each having a 75 perforated lug 10 with which the end of the spring 11 is engaged. The other end of the spring 11 is engaged with an outer fastener 12, shown in detail in Fig. 5, which has a perforated lug 13 to receive the end of the 80 spring and its body 14 being swiveled in a recess 15 in the outer rib 7 and having a groove 16. A disk 17 having a radial slot 18 engages the groove 16 and lies within the recess 15 and thereby retains the fastener 12. 85 The tension of the spring 11 serves to hold the disk 17 inside the recess 15, preventing the disk from slipping sidewise and disengaging the groove 16, yet forming a device easy to disengage whenever it is desired to 90 do so.

To house the springs for excluding foreign substance, side plates 19 are arranged on each side of the felly and are secured thereto by bolts 20. The outer edges of the plates 95 19 have a close fit slidably on the side faces of the outer felly member 2. It will be noted that the springs 8 exert an inward tension on both outer felly sections 3 tending to hold the two sections 3 interlocked with each 100

other at the rabbet 4, so that no fastening devices are necessary as the combined pull of all the springs is very great.

In operation when the felly sustains a load, the felly member 1 descends toward the road, thereby becoming eccentric to the outer felly member 2 which is supported by the road. All points on the inner felly member 1 thus move in strict vertical lines an equal distance. Thus if the eccentricity thus produced is one half an inch, each point on the circumference of the inner felly will move downward toward the ground one half an inch and will, therefore, move the inner ends of all the springs one half an inch closer to the ground and as the outer ends of all the springs are held stationary by the outer felly member, each spring will therefore be tilted into an angular position such that its opposite ends occupy horizontal planes one half an inch apart, measured vertically. The result of this is that in assuming these angular positions the springs will all be stretched an equal amount and when the load is removed, the reaction of the springs will cause them to all move back to a horizontal position which will restore the inner felly member to concentricity with the outer felly member. It will be seen that from this construction even if the springs are not of the same tension or are unevenly distributed that they will nevertheless all coöperate in the aggregate to resist eccentric movement of the felly members, and will all coöperate to restore the inner felly member to center position when the load is removed. Thus, assuming that a number of springs have been removed from the upper portion of the wheel in Fig. 1, and the load is placed on the wheel, the springs although unevenly distributed will all be moved to the same angular degree and will all sustain the same stretch, and will act together to resist the eccentric movement of the members and will thereby resist the load to a degree corresponding to the aggregate pull exerted upon all the springs which are present. It is not necessary, therefore, that all of the springs be of exactly the same tension or that they be perfectly distributed, as it is the aggregate resistance of the springs which resist and determine the amount of eccentric movement. It is necessary that the springs be substantially balanced in number and pull on opposite sides of the rib 6 in order to maintain the two felly members against transverse movement with respect to each other. It is also to be noted that under light loads and small vibrations of the felly that the springs will be swung laterally but a slight distance and the springs will permit of the lateral movement even though the springs are of considerable strength. This

enables springs to be used which are capable of sustaining the heaviest loads and yet maintaining sensitiveness to slight variations with light loads. As the load is increased the resistance of the spring is increased at a faster ratio than though the spring were disposed radially. Thus a slight deflection of a spring angularly stretches the spring but a slight amount and is resisted but slightly, while as the eccentricity of the spring increases the angularity of the springs increases, and the ratio of its resistance builds up and increases with the increase in angularity. Where the springs are in line with the felly members concentrically, the springs pull straight against each other and exert but little lifting effect when moved slightly angularly, but when their angle becomes more acute, the two sets of springs combine in their resistance to support the inner member.

It will now be apparent that this disposition of the parts permits one felly member to move circumferentially with respect to the other a certain amount, determined by the resistance of the springs and that this relative movement will place all of the springs uniformly in the same angular position and cause them to uniformly resist this motion. This results in any shock from the motor being first imparted to the springs which absorb that shock and the springs in reacting transfer the greater portion of the power that had thus been stored up in them, back to the outer felly member to propel the wheel. The shock is softened during its absorption by the stretching of the springs and also during the subsequent transfer from the springs to the outer felly member. This results in enabling heavy loads to be started with much less power than where the starting shock is not first absorbed and then retransmitted to the traction member of the felly. This minimizes stalling of the motor when starting an excessively heavy load and thereby enables motors of less power to be employed under such conditions in addition to relieving the machinery from undue strains caused by the momentum or striking force of the fly-wheel.

What I claim is:

1. A spring felly comprising two felly members, the outer felly member having two ribs, said ribs having recesses, spring fasteners extending into said recesses and having grooves, slotted disks in said recesses engaging the grooves of the spring fasteners, two sets of springs, the outer ends of the respective sets being engaged with the spring fasteners in said ribs, and means connecting the inner ends of the two sets of springs to the inner felly.

2. A spring felly comprising two felly

members, the outer felly member having two ribs, said ribs having recesses, spring fasteners extending into said recesses and having grooves, slotted disks in said recesses engag-
5 gaging the grooves of the spring fasteners, two sets of springs, the outer ends of the re-
spective sets being engaged with the spring fasteners in said ribs, a rib on the inner felly, and spring fasteners in said rib to

which the inner ends of the respective sets 10 of springs are attached.

In testimony whereof, I have hereunto set my hand at Winters, California this 17th day of February, 1913.

FRANK MONROE PRATHER.
